US00D890128S

(12) **United States Design Patent** (10) Patent No.: **US D890,128 S**
(45) Date of Patent: **** Jul. 14, 2020**

(54) **WIRELESS EARPHONE**

- (71) Applicant: **LG Electronics Inc.**, Seoul (KR)
- (72) Inventors: **Dongsoon Kim**, Seoul (KR); **Seungyup Lee**, Seoul (KR); **Byungsoo Oh**, Seoul (KR); **Sojin Kim**, Seoul (KR)
- (73) Assignee: **LG Electronics Inc.**, Seoul (KR)
- (**) Term: **15 Years**
- (21) Appl. No.: **35/506,820**
- (22) Filed: **Dec. 6, 2018**

(80) **Hague Agreement Data**

- Int. Filing Date: **Dec. 6, 2018**
Int. Reg. No.: **DM/200309**
Int. Reg. Date: **Dec. 6, 2018**
Int. Reg. Pub. Date: **Jun. 7, 2019**
- (51) LOC (12) Cl. **14-01**
(52) U.S. Cl. **D14/205**
(58) Field of Classification Search
USPC D14/205-206, 216, 223, 226, 249, 252

(57) **CLAIM**

The ornamental design for a wireless earphone, as shown and described.

DESCRIPTION

1. Wireless earphone
1.1 is a front perspective view of a wireless earphone showing our new design;
1.2 is a front view thereof;
1.3 is a back view thereof;
1.4 is a left view thereof;
1.5 is a right view thereof;
1.6 is a top view thereof; and
1.7 is a bottom view thereof.

The broken lines depict portions of the wireless earphone that form no part of the claimed design.

1 Claim, 7 Drawing Sheets(56)
